UNITED STATES PATENT OFFICE.

FLORA MASON NICHOLSON, OF WASHINGTON, DISTRICT OF COLUMBIA.

DESIGN FOR A RECEPTACLE FOR TOILET ARTICLES OR SIMILAR ARTICLE.

Application filed February 14, 1927. Serial No. 20,760. Term of patent 7 years.

To all whom it may concern:

Be it known that I, FLORA MASON NICHOLSON, a citizen of the United States, residing at the city of Washington, District of Columbia, have invented a new, original, and ornamental Design for Receptacle for Toilet Articles or Similar Article, of which the following is a specification, reference be-

ing had to the accompanying drawing, forming part thereof.

The figure is a perspective view of a receptacle showing my new design.

I claim:

The ornamental design for a receptacle for toilet articles or similar article, as shown.

FLORA MASON NICHOLSON.
